Industries Research Association, London, Eng-
land, a British company

Application March 15, 1932, Serial No. 599,006
In Great Britain May 9, 1931

14 Claims. (Cl. 200—150)

This invention relates to electric switches and like interrupters for electric circuits in which the contacts or electrodes separate when the circuit is broken and a blast of fluid such as gas or oil, or a mixture of gas and liquid, or a spray of liquid particles, is forced towards the arc set up between the electrodes.

It has already been proposed to construct an electric switch with a piston on which one of the electrodes is mounted and arranged so that a spring is compressed when the switch is closed so that when the circuit breaker or switch opens again the spring acts on the piston to force fluid into the arc. The object of the present invention, however, is to provide a simple and efficient means for setting the piston and a spring or its equivalent ready for operation and for enabling the piston to be insulated from the moving electrode when the latter has fully opened.

In all high tension circuit breakers the problem is to extinguish the arc set up when the electrodes separate, effectively and quickly. In the ordinary explosion pot when the electrodes separate pressure for extinguishing the arc is generated in a more or less closed pot, and although some products of arcing will escape around the retracting electrode, movement of fluid in the neighbourhood of the arc is necessarily sluggish until the moving electrode leaves the pot when the arc stream at the aperture is surrounded by a fluid blast. In these conditions it is improbable that oil will be driven radially into the arc gap and in any event a considerable interval of time in the circumstances must elapse between the start of arcing and the application of any blast to any part of the arcing region with the result that during this period much of the oil is blown out of the pot without any useful action on the arc. Furthermore, in the ordinary explosion pot when interrupting small currents there is often insufficient energy available to set up any appreciable blast. The present invention provides means for producing a blast which can act effectively when interrupting currents at the low part,

or at any other part of the current range. The invention provides structures ensuring that the blast comes into immediate effective action at the start of arcing and ensuring that oil is driven radially into the arc gap by a pressure which is greater than the arc pressure and is therefore able to overcome the latter. A piston is therefore provided to force oil through and across the arc into contact with the switch electrodes and through a hollow electrode in order to produce rapid and effective cooling and extinguishing of

the arc. This movement of the fluid is produced by the piston and the pressure set up by the products of arcing is, according to the present invention, employed to assist the action of a spring in actuating the piston.

The invention may be applied to the form of switch set forth in our copending patent application Serial No. 607,470 filed April 25th, 1932, in which a piston is provided and is arranged so that pressure set up by the products of arcing acts on opposite surfaces, in which case, the energy stored in the spring is used to better advantage or is reinforced in moving the piston by the resultant pressure of the arcing products acting on one of the faces of the piston.

In order that the invention may be clearly understood and readily carried into effect, some examples of constructions of circuit breakers in accordance with the invention will be described with reference to the accompanying drawings, in which:—

Figure 1 is a central vertical section, and Figure 2 is a cross-section on the line II—II in Figure 1 of one form of the improved switch, in which the pressure of the arc products acts more or less differentially on both faces of a piston as set forth in the said copending application Serial No. 607,470 filed April 25th, 1932.

Figure 3 is a central vertical section of a further form of switch in accordance with the invention, the action of the spring being only supplemented by the pressure of the arc products if an outlet at the top is made sufficiently small; and

Figure 4 is a horizontal cross-section on the line V—V in Figure 3.

Referring first of all to Figures 1 and 2, a switch structure consists of a metal container 1 substantially of cylindrical shape with a metal top plate 2 screwed into the cylindrical wall and secured to the lower end of the lead-in insulator 3. The fixed contacts 4 of the switch are carried on a downwardly extending tube 5 which is screwed into a recessed plate 6 secured to the top plate 2.

An annular piston 7 fits around the tubular extension and slides with the outer surface of its top disc 8 in contact with the cylindrical wall of the container 1 and with the outer surface of its lower disc 9 in contact with a tubular member 10 which is screwed into the container 1 immediately above the clamping ring 10a which holds the base of the switch in position. The moving contact of the switch is a solid contact 11 and is shown in the closed position within the fixed contacts 4. The piston 7 is also shown in its uppermost position in which it has been pushed

by the spring 12 which is thus fully extended. The piston 7 has at the top a number of circumferentially spaced castellations 13 which in the form illustrated do not serve as stops coming into contact with the plate 2, but merely afford additional guiding surface for the piston 7. As already mentioned, in this case, the pressure set up by the products of arcing when the contacts 4 and 11 separate act differentially on the lower surface of the disc 9 of the piston and on the upper surface of the disc 8, and as the upper surface is larger than the lower surface, there is an unbalanced pressure tending to push the piston 7 downwards. However, in accordance with the present invention, a spring 14 is provided intended to give the starting downward movement to the piston 7 so that fluid such as oil or gas may be forced towards the contacts at or before the time that arcing commences, which, owing to the inertia of the moving parts could not occur in the absence of the spring 14. It will be noticed that the upper part of the tube 5 is divided to leave spaces between four webs 15, and a spider ring 16 is placed on the top of the ring 8 of the piston with radial arms 17 passing between the webs 15. Then a thrust ring 18 is placed within the tube 5 on top of the radial arms 17 of the spider 16 and the spring 14 bears on the thrust ring 18. The spring 14 therefore, presses on the piston 7 and the latter is held in the uppermost position shown by reason of the fact that the moving switch contact 11 acts through a rod 19, which, in this example, is of insulating material extending down from the spider 16 so as to press up the spider and compress the spring 14 allowing the spring 12 to raise the piston to the position shown. Seep holes are shown at 20 in the top plate 2 and at 21 in the fixed contacts 4.

When the switch is opened the parts act as follows:—The moving contact 11 is moved downwards, for example, by the usual cross-bar and therefore relieves the pressure on the rod 19 and on the spring 14. The latter immediately begins to expand to push down the piston 7, but at the same time an arc is struck between the fixed contacts 4 and the moving contacts 11. The products of arcing set up a pressure acting on the upper and lower faces of the piston, because the pressure passes through the central passageway in the fixed contacts 4, through the windows between the webs 15 of the tube 5 and therefore has access to the top of the piston 7. If therefore the spring 14 is pressed downwardly on to the piston, this differential pressure takes control and moves the piston fully down until the pressure escapes through an exhaust port 22, by which time the arc will have been extinguished by the oil or other insulating fluid which has been driven across the arc, through the central passageway in the contacts 4, and ultimately out of the exhaust port 22 by the motion of the piston 7. At this stage the switch has reached the fully open position and by reason of the release of pressure above the piston the spring 12 will be able to lift the latter and as soon as the switch is closed, the piston will be completely reset into its fully raised position because the moving contact 11 is lifted to take off the pressure of the spring 14.

Of course, the male and female contacts 4 and 11 may be replaced by butt contacts, in which case, the rod or plunger 19 would be suitably elongated.

In the form of construction illustrated in Figures 3 and 4, corresponding parts are numbered in the same way as in Figures 1 and 2. In Figure

3, the lower part of the switch container is not shown but it is identical with that shown in Figure 1 except for the tubular member 10 which is not needed in the embodiment of Figure 3. In this case, however, the piston 7 has surfaces of the same area on top and bottom so that there is no differential pressure exerted, and the whole of the downward movement of the piston 7 is in this case produced by the spring 14 which is of larger diameter than in Figure 1 and presses directly upon the piston 7. When the switch is opened the downward movement of the piston forces oil up through the passageway in the centre of the contacts 4 and through the spaces between the fixed switch contact 4 and the moving contact 11, and in this case, the oil so forced up and other products can be so swept out that an exhaust outlet 22, which is at the top of the container, is therefore constantly open as there is no need to retain pressure until the piston has reached practically the bottom of its stroke. In this case also, the piston has at the top castellations 13 for increasing the guiding surface. The size of the exhaust outlet 22 may be varied from a mere seep hole up to the point at which the whole of the top of the container 1 is practically open. The smaller the outlet 22, the more nearly equal is the pressure of the fluid on both sides of the piston 7 and the less interference is there with the free action of the spring 14. The rod 7a of insulating material screwed into the piston 7 and guided in the cover plate 2 is connected to a switch in an auxiliary trip circuit so as to close that switch only when the main circuit breaker is fully closed. By this means tripping of the circuit breaker is prevented until the piston 7 has reached its uppermost position.

From the above examples, it will be understood that in cases in which a piston is used to drive liquid towards the arc, one or more fine seep holes as shown at 23 in Figure 3 may also be provided through the piston to regulate the level of any fluid which may be used below the piston and to prevent the formation of a gas trap or the seep hole 23 in Figure 3 may be formed at any desired level in the lower part of the side wall of the piston 7 to determine the boundaries of a gas trap. These holes, however, must not be large enough to allow any serious escape of liquid through them during the opening operation.

Since, generally speaking, the spring or springs employed in accordance with the present invention, act in the same direction as the springs usually provided for opening circuit breakers, these usual springs may be dispensed with in some cases, and the spring, for example, the spring 14 in Figure 3, acting through the piston 7 and stem 19 would open the circuit breaker. This action may be facilitated by enlarging the upper end of the moving contact 11 and including a resilient or yielding joint in its operating mechanism so that, in the closed position, the contact 11 butts against the lower end of the stationary contact 4 instead of entering into it.

We claim:—

1. An electric circuit interrupter, comprising in combination, a casing formed with slide surfaces, a piston mounted within said casing to slide on said surfaces and formed with a passageway, a fixed electrode mounted in said casing, a movable electrode mounted so that products liberated by the arc set up upon separation of said electrodes are placed in communication with both faces of said piston through the passageway thereof, a resilient energy-storing device in oper-

- ative connection with said piston so as to drive said piston when released to cause fluid to move towards the arc, and current connections to said electrodes, said movable electrode being in operative connection with said energy-storing device so as to stress the latter and store energy therein upon closure of the circuit interrupter.
2. An electric circuit interrupter comprising in combination, a casing shaped to form an internal piston chamber, a piston mounted to slide in said chamber and formed with opposite faces of different effective areas, a pair of relatively movable electrodes mounted in said casing so that products liberated by the arc set up on separation 10 of said electrodes are placed in communication with both faces of said piston, a resilient energy-storing device mounted to impart energy to said piston so as to assist the differential pressure of the arc products in effecting the operative stroke 15 of said piston, and current connections to said electrodes, one of said electrodes being movably mounted in operative connection with said resilient device so as to stress the latter and store energy therein upon closure of the circuit interrupter.
3. An electric circuit interrupter comprising in combination, a casing shaped to form an internal piston chamber, a pair of relatively movable electrodes mounted in said casing, a piston arranged 20 to slide in said piston chamber, a resilient energy-storing device in operative connection with said piston so as to drive the latter to cause fluid to move towards the arc set up between said electrodes upon separation thereof, and current connections to said electrodes, said piston and one 25 of said electrodes being formed with a passageway connecting the spaces in the said casing on the two sides of said piston and one of said electrodes being operatively connected to said piston to cause storage of energy in said resilient device during 30 closure of the circuit interrupter.
4. An electric circuit interrupter comprising in combination, a casing formed with an internal piston chamber, a piston mounted within said casing to slide in said chamber and formed with two faces of different effective area, a fixed electrode mounted in said casing, a movable electrode mounted to co-operate with said fixed electrode, a resilient energy-storing device in operative connection with said piston so as to drive said piston when released to cause fluid to move towards the arc and current connections to said electrodes, said piston and said movable electrode being formed with a passageway connecting the spaces 45 in said casing on the two sides of said piston and allowing the arcing products to have access to both faces of said piston.
5. An electric circuit interrupter comprising in combination, a casing formed with an internal piston chamber, a fixed electrode mounted in said casing, a movable electrode mounted to co-operate with said fixed electrode, a piston insulated from said electrodes and mounted within said casing to slide within said piston chamber and formed with a passageway to provide communication between the arc set up upon separation of said electrodes and the spaces within said casing on both sides of said piston, a resilient energy-storing device in operative connection with said piston so as to drive 50 said piston when released to cause fluid to move towards the arc, and current connections to said electrodes, said movable electrode being in operative connection with said resilient device so as to stress the latter and store energy therein upon 55 closure of the circuit interrupter.
6. An electric circuit interrupter comprising in combination, a casing serving as an arcing chamber and shaped to form an internal piston chamber, a fixed electrode mounted in said casing, a movable electrode mounted to co-operate with said fixed electrode, a piston exposed to the pressure set up by the products of arcing within said casing, said piston being mounted to slide within said piston chamber and being formed with a passageway permitting the pressure set up by the products of arcing to have access to both faces of said piston, means for moving said movable electrode in the same direction as said piston both during opening and closure of the circuit interrupter, a resilient energy-storing device in operative connection with said piston so as to drive said piston when released to cause fluid to move towards the arc set up between said electrodes upon separation thereof, and current connections to said electrodes, said movable electrode being in operative 60 connection with said resilient device so as to stress the latter and store energy therein upon closure of the circuit interrupter.
7. An electric circuit interrupter comprising in combination, a casing shaped to form an internal piston chamber, a piston mounted to slide within said chamber and formed with a passageway, a resilient energy-storing device mounted to act upon said piston so as to drive said piston when released to cause fluid to move towards the arc 65 formed between said electrodes upon separation thereof, a fixed electrode mounted in said casing, a movable electrode mounted so that the products liberated by the arc set up upon separation of said electrodes are afforded access to the spaces within said casing on both sides of said piston through the passageway thereof, a thrust member interposed between said movable electrode and said energy-storing device, and current connections to said electrodes, said movable electrode 70 being operative through said thrust member and said piston to stress said energy-storing device and store energy therein upon closure of the circuit interrupter.
8. An electric circuit interrupter comprising in combination, a casing shaped to form an internal piston chamber, a pair of relatively movable electrodes mounted in said casing, a piston mounted to slide within said piston chamber so as to force fluid towards the arc set up between said electrodes upon separation thereof, and having its opposite faces located in closed pressure-retaining spaces within said casing, a resilient energy-storing member in operative connection with said piston to effect the operative stroke 80 thereof and current connections to said electrodes, one of said electrodes being mounted to move and being operatively connected to store energy in the said resilient member during the closing movement of the circuit interrupter and the other of said electrodes being formed with a hollow passageway to enable pressure set up by the products of arcing to have access to both faces of said piston and to act on one of the faces of said piston to assist the action of said 85 resilient member.
9. An electric circuit interrupter comprising in combination, a casing shaped to form an internal piston chamber, a pair of relatively movable electrodes mounted in said casing, a piston formed with its opposite surfaces of unequal areas mounted to slide within said piston chamber so as to force fluid towards the arc set up between said electrodes upon separation thereof, and having its opposite surfaces located in closed pressure-retaining spaces within said casing to assist the action of said resilient member.

- sure-retaining spaces within said casing, a resilient energy-storing member in operative connection with said piston to effect the operative stroke thereof and current connections to said electrodes, one of said electrodes being mounted to move and being operatively connected to store energy within said resilient member and said other electrode being formed with a passageway enabling products of arcing to have access to both faces of said piston to exert a differential pressure assisting the action of said resilient member during the opening movement of the circuit interrupter.

10. An electric circuit interrupter comprising in combination, a casing shaped to form an internal piston chamber, a pair of relatively movable electrodes mounted in said casing, a piston shaped with opposite faces of different effective areas and mounted to slide within said piston chamber so as to force fluid towards the arc set up between said electrodes upon separation thereof, said piston being formed with a passageway to allow access of arc products to both faces thereof, a resilient energy-storing device in operative connection with said piston to effect the operative stroke thereof and current connections to said electrodes, one of said electrodes being mounted to move and being operatively connected to store energy in said resilient device but independently of said piston, so that any arc formed upon opening or closing the circuit interrupter sets up pressure which may be expended upon said piston to move same without acting to retard or accelerate the motion of said moving electrode.

15. An electric circuit interrupter comprising in combination, a casing shaped to form an internal piston chamber, a pair of relatively movable electrodes mounted in said casing, a piston mounted to slide within said piston chamber so as to force fluid towards the arc set up between said electrodes upon separation thereof, a spring in operative connection with said piston to effect the operative stroke thereof, a second spring weaker than said first mentioned spring and connected to urge said piston into its fully set position during closing of the circuit interrupter and current connections between said electrodes, one of said electrodes being mounted to move and being operatively connected to store energy in said first-mentioned spring during closing of the circuit interrupter and current connections between said electrodes, one of said electrodes being mounted to move and being operatively connected to store energy in said first-mentioned spring independently of movement of said piston during the closing movement of the circuit interrupter and said piston being shaped so as to afford the arc products access to one face thereof so as to exert pressure thereon to assist the action of said first-mentioned spring.

20. An electric circuit interrupter comprising in combination, a casing shaped to form an internal piston chamber, a piston formed with faces of unequal effective areas and mounted within said piston chamber to divide same into primary and secondary chambers connected together by a passageway passing through said piston, a pair of relatively movable electrodes mounted in said casing and separable to form an arc in said primary chamber so as to set up pressure operative upon both faces of said piston, a spring in operative connection with said piston so as to urge same in the same direction as the pressure acting on the larger face thereof, a second spring weaker than said first-mentioned spring and connected to urge said piston into its fully set position during closing of the circuit interrupter and current connections between said electrodes, one of said electrodes being mounted to move and being operatively connected to store energy in said first-mentioned spring but independently of said piston, during the closing movement of the circuit interrupter.

25. An electric circuit interrupter comprising in combination, a casing shaped to form an arc-enclosure, a pair of relatively movable electrodes mounted in said casing to separate to form an arc in said enclosure, a pumping device having two operating surfaces of unequal effective areas and both in communication with said arc-enclosure and operative to force fluid towards said arc, a resilient energy-storing member in operative connection with said pumping device to effect the operative stroke thereof and current connections to said electrodes, one of said electrodes being mounted to move and being operatively connected to store energy in said resilient member and the products of arcing having access to the two operating surfaces of said pumping device to exert a differential pressure assisting the action of said resilient member during the opening movement of the circuit interrupter.
